UNITED STATES PATENT OFFICE.

FRANK C. BATES, OF KANSAS CITY, MISSOURI, ASSIGNOR TO JOHN B. STADER, OF KANSAS CITY, MISSOURI.

VENDING-MACHINE.

1,384,586.

Specification of Letters Patent. Patented July 12, 1921.

Application filed August 4, 1920. Serial No. 401,188.

To all whom it may concern:

Be it known that I, FRANK C. BATES, a citizen of the United States, residing at Kansas City, in the county of Jackson and State of Missouri, have invented certain new and useful Improvements in Vending-Machines; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 This invention relates to vending machines and particularly to a machine capable of vending different sized articles; for example, the mechanism is so arranged that the machine is capable of vending pencils, cigarettes 20 or other relatively thin articles, or cigars or other relatively thick articles, the variations in the size of the articles to be vended being compensated for by appropriate adjusting devices associated with the ejector mechanism.

25 In the drawings,

Figure 1 is a perspective view of a machine constructed in accordance with my invention, parts being broken away to show the 30 interior mechanism, the ejector being in article-receiving position.

Fig. 2 is a similar view showing the ejector in article-discharging position.

Fig. 3 is a view of the adjustable ejector 35 actuator.

Fig. 4 is a fragmentary, perspective view of one end of the ejector, and

Fig. 5 is an end view of the ejector gate clip or slide.

40 The invention is illustrated as consisting of a receptacle or casing 1, in the top of which is a fixed hopper 2 to receive a carton or box 3 at its inlet, the box or carton presumably containing the articles to be vended. The 45 hopper 2 has a retracted opening at its lower end, discharging into an ejector whereby the articles may be directed from the hopper to the discharge slot or opening 4.

50 The ejector is shown as consisting of a curved plate or segment of a cylinder 5, at the respective ends of which are segmental arms 6 and 7, fixed to a rock shaft 8, jour-

naled in bearings 9 and 10 on the supporting bars 11 and 12, carried by the interior of the machine. The front edges of the segmental arms or levers 6 and 7 are faced by a plate 13, the ends 14 and 15 of which extend beyond the arms 6 and 7 to constitute guides for vertically sliding clips or guide members, one of which is shown in detail in Fig. 5 and 60 designated by the reference numeral 14'. Each of the clips consists of a plate bent back upon itself to form a return edge 15' to provide a groove 16 engaging the edge of the plate 13 and each plate 14' carries a barrel 65 17 constituting a bearing for a rotatable shaft 18, extending across the plate 13 and carrying a swinging ejector plate or gate 19, adapted to swing toward and away from the plate 13, as will be presently explained.

70 On the end of the shaft 18 is a pinion 20, adapted to mesh with the segmental rack 21 on the ejector actuator, shown as a U-shaped member 22 including the standards 23 and 24, slidable in the recessed blocks 25 and 26 secured to the cross bar 12. The standard 23 is provided with ratchet teeth 27, adapted to be engaged by a spring-pressed detent 28, carried by the socket member 25 whereby the member 22 may be raised and lowered and 80 held in any adjusted position by the detent 28. Access to the detent may be had through the rear of the casing 1, which is provided with a rear door, not shown.

85 Journaled in one side of the casing 1 is a spring retracted rock shaft 29, having a hand lever 30 accessible from the outside of the casing and a crank arm 31 on the interior of the casing adapted to abut against a coin pan or receiver 32, normally registering with 90 a coin slot 33 having an inlet opening accessible from the outside of the case and a discharge opening on the inside of the case.

95 The coin pan or receiver 32 is provided with a slot or opening 34 through its wall, adapted to be closed by a coin, check or token introduced through the slot 33. The initial downward movement of the coin within the pan or receiver 32 will be limited by the segmental or curved slot or plate 35, carried by 100 the side of the case and extending across the opening 34 of the coin pan so that initially the coin will be held in the pan to be engaged by the crank 31. For example, if the parts

- are in the position shown in Fig. 2 and a coin, check or token is introduced through the slot 33, it will fall into the pan 32 and rest against the stop 35. Then if the operator presses rearwardly upon the handle 30, the crank arm 31 will contact with the coin held in the pan carried by the arm 7 and a continued rearward swinging movement of the handle 30 will carry the ejector, including 5 the arms 6 and 7, the member 5 and the plate 13, rearwardly. Since the members 14¹ are carried by the edges of the plate 13, they will be carried rearwardly, causing the pinion 20 to roll over the rack 21 to swing the 10 gate 19 upwardly against the lower edge of the hopper 2. The member 5 acts as a valve or gate to normally close off the discharge end of the hopper 2 but as it swings rearwardly, it will move past the hopper opening, allowing one of the articles to drop 15 between the plate 13 and the gate 19. When it has reached that position, the coin will have moved past the end of the stop 35 and will have dropped to the bottom of the case, 20 allowing the spring 36 to retract the ejector valve toward the front of the machine. In doing this, the pinion will be caused to roll or rotate in the opposite direction, swinging the ejector gate 19 downwardly away from 25 the plate 13 toward the opening 4 until it assumes the position shown in Fig. 2, whereupon the article will be dropped through the opening 4 and the device will be ready to be again operated. 30
- 35 It is to be understood, of course, that as soon as the operator releases the handle 30, the spring 37, wound about the shaft 29 and fixed to one side of the case 1, will rock the shaft to swing the handle 30 and the crank 40 31 back to normal position, as shown in Fig. 2.
- If articles of relatively small diameter are to be vended, the base of the gate 19 must be relatively high with respect to the 45 plate 13; otherwise, more than one article would drop into the space between 13 and 19. In such event, the rack 22 is raised relatively high and held in such position through the means of the detent or pawl 28.
- 50 When the rack is adjusted vertically, the members 14¹ will slide vertically on the edges of the plate 13 to adjust themselves to accommodate the rack and as they move up, they, of course, will carry the plate 19 55 with them.
- If relatively thick articles are to be vended, the U-shaped member 22 will be lowered. In which event, the members 14 will drop or move downwardly along the edges 60 of the plate 13 so that the pinion 20 may engage the rack teeth. In that event, the space between 13 and 19 will be relatively large and thicker articles may be received therein.
- 65 It will be apparent from the foregoing

that the device will vend articles of different thicknesses between two extremes and that it can be readily adjusted whenever the occasion demands. It will be further apparent that the device is simple in operation and that it is well adapted to perform the function for which it is intended. 70

What I claim and desire to secure by Letters-Patent is:

1. In a vending machine, an article-containing hopper, a swinging valve closing and opening the discharge end of the hopper, a swinging gate slidably mounted on the valve, and means for rotating the gate. 75

2. In a vending machine, an article-containing hopper, a swinging valve closing and opening the discharge end of the hopper, a swinging gate slidably mounted on the valve, a pinion mounted rigidly with respect to the gate, and a vertically adjustable rack for engagement with said pinion. 80

3. In a vending machine, an article-containing hopper, a swinging valve closing and opening the discharge end of the hopper, a swinging gate slidably mounted on the valve, a pinion mounted rigidly with respect to the gate, a vertically adjustable rack for engagement with said pinion, and means for holding said rack in any adjusted position. 90

4. In a vending machine, a hopper having a discharge opening at its lower end, a valve for closing and opening the discharge end of the hopper, a wall carried by the valve, a vertically adjustable gate mounted on the wall and having swinging movement with respect thereto, and means for actuating the valve and gate. 100

5. In a vending machine, a hopper having a discharge opening at its lower end, swinging arms mounted below the discharge end of the hopper, a curved valve plate carried by the upper ends of the arms, an ejector wall carried by the forward edges of the arms, a swinging gate mounted on the ejector wall, a segmental rack, a pinion rigid with the swinging gate and meshing with the rack, and means for actuating the arms to function the valve and to cause the gate to swing as the pinion rolls over the rack. 105

6. In a vending machine, an article-containing hopper having a discharge opening at its lower end, a rock shaft below the discharge end having upstanding arms, a curved valve plate carried by the arms and movable beneath the discharge end of the hopper, an ejector plate carried by the forward edges of the arms and having ends extending beyond the ends of the arms, clips vertically adjustable with respect to said ejector plate and having portions overlapping the arms, a shaft carried by said clips, a gate rigidly connected to the shaft, a pin- 115

ion on one end of the shaft, a segmental rack beneath the pinion, means for vertically adjusting said rack to compensate for vertical movement of the clips, and means for swinging the arms to actuate the ejector, the valve and the gate.

7. In a vending machine, an article con-

tainer, an ejector below the container, and means for raising and lowering the ejector for adapting the machine to vend various sized articles.

In testimony whereof I affix my signature.

FRANK C. BATES.
